UNITED STATES PATENT OFFICE.

WILLIAM C. OSTERHOLM, OF CHICAGO, ILLINOIS.

UNIVERSAL TAPPING-MACHINE.

1,395,353.

Specification of Letters Patent.

Patented Nov. 1, 1921.

Application filed December 26, 1918. Serial No. 268,344.

To all whom it may concern:

Be it known that I, WILLIAM C. OSTERHOLM, a citizen of the United States, residing at Chicago, in the county of Cook, and 5 State of Illinois, have invented certain new and useful Improvements in Universal Tapping Machines, of which the following is a full, clear, and exact specification.

This invention relates to tapping machines, and machines of like character.

In order that a tapping machine may successfully perform its function, and operate efficiently and accurately, the tool must be so mounted that it can be easily and 15 quickly adjusted to the desired position, or, in other words, can be easily and quickly centered. Unless the tap is accurately centered the screw thread will not be true, and the tap itself may be broken. The object 20 of this invention, therefore, is to render the operation of tapping accurate and efficient.

A further object is to reduce the tapping expense by eliminating breakage, and shortening the time required for the tapping operation.

With these and other objects in view, the invention is embodied in an adjustable mounting for the tool, so constructed that the tool can be quickly and easily adjusted 30 in the desired direction, and can be held or locked in the desired position of adjustment.

A further feature of the invention is embodied in a work holding means for securely holding the work against accidental movement so that the adjustment of the tool need not be changed after the tool has been properly aligned with the work.

In the accompanying drawings the invention has been illustrated in connection 40 with a tapping machine, but it should be understood that my invention is equally desirable on drilling and reaming machines, and that the use on such machines is contemplated, and it is my intention to comprehend all such uses in the appended claims.

I have illustrated one embodiment of my invention in the drawings accompanying this application, and in these drawings—

50 Figure 1 shows a front elevation of my improved machine;

Fig. 2 is a side elevation of the construction shown in Fig. 1;

Fig. 3 is a detail view showing the work 55 holding means; and

Fig. 4 is a sectional view on an enlarged scale showing the hand-wheel and lever for operating the tool.

The invention is illustrated in connection with an upright tapping machine, including 60 the usual pedestal 10, having secured thereto a slide base 11. A work table support 12 is slidably mounted on the base 11, and has a dove-tail connection therewith, and a clamping screw 13 secures the work table 65 support in place on the base 11. A base 14 is also slidably mounted on the slide base 11, being connected therewith by a dove-tail connection, and having a clamp 15 for securing the base 14 in place on the slide 70 base 11. The work table 16 is rotatably mounted on the work table support 12, and is provided with a series of apertures located in the circumference of a circle described with the center of rotation of the table as 75 the center of the circle. A locking pin 17 is reciprocably mounted on the work table support 12, and is located in a position to enter any one of the apertures in the work table above described. The pin 17 is provided at its lower end with a slot, through 80 which extends one arm of a lever 18, which is pivoted at 19 to the work table support, and has its opposite arm 20 actuated in a downward direction by means of a spring 85 pressed plunger 21 also carried by the work table support.

A bracket 22 is bolted to the side of the support 12, and has pivoted thereto at its upper end an arm 23, which adjustably carries at its outer end a work holding member 24. The pivot shaft of the arm 23 has secured thereto at one end a crank arm 25, to which is pivotally secured a rod 26. The rod 26 is normally pressed upwardly by a 90 spring 27, which bears at one end against a collar 28 secured to the rod 26, and at its opposite end against an outwardly projecting lug 29 carried by the slide base 11. Near its lower end the rod 26 has secured thereto 95 a hanger 30, having outwardly extending projections 31 and 32. The lower end of the rod 26 extends into a hanger 33, having corresponding outwardly extending projections 34 and 35. The projections 32 and 100 34 and 31 and 35 are connected respectively by means of coil springs 36 and 37. The hanger 34 is secured to a rod 38, which is pivotally connected at its lower end to a foot treadle 39 pivoted at 105 40 to the base of 110

the pedestal. The treadle is provided near its front end with a slot 41 and a lug 42 projecting over a portion of the slot.

In order to lock the treadle in its lower position, I have provided a pivoted latch 43 having a notch 44 in one edge thereof, and normally pressed forwardly by means of a spring 45. As the treadle is pushed down the wall of the slot engages the upper beveled edge 46 of the treadle, and forces the latch rearwardly until the treadle reaches its lowermost position, when the lug 42 comes into engagement with the notch 44, and the treadle is locked against return movement. As the treadle is pressed downwardly the movement of the treadle is communicated to the rod 38, and through the hangers 33 and 30, and the springs 36 and 37 to the rod 26. From the rod 26 the movement is communicated through the crank arm 25 and arm 23 to the work holding member 24.

The work clamping means provides a quick operating mechanism for securing the work to the table and may be as quickly released to permit removal of the work after the tapping or drilling operation. Owing to the yielding connection 31-37 work of varying sizes may be clamped to the table 16 without adjustment of the clamping means.

The adjustable mounting for the tool will now be described. The base 14 above described supports vertical standards 47 for the vertically adjustable support frame 48, which is vertically slidable on the standards 47, and is provided with a split sleeve clamping member 49, which secures the frame in the desired position of adjustment. The standards 47 are connected at their upper ends by a cross rail 50, to which are secured idlers 51.

A counterbalancing means is provided for the supporting frame 48, and consists of a series of weights 52 carried by suitable casting 53 secured to the base 14, and connected by means of a cable 53' to the supporting frame 48, the cable passing over the idlers 51. The tool 54 and tool spindle 55 are mounted for endwise and rotary movement in a saddle or adjustable supporting frame 56. The frame 56 is horizontally adjustable on guideways 57 carried by the supporting frame 48, and is provided with overlapping flange members 58 which secure the frame 56 against displacement. A clamping screw 59 is carried by the frame 56, and clamps the flanges against the ways in such a manner as to hold the saddle or frame 56 in the desired position of adjustment.

An operating wheel 60 is secured to the outer end of the spindle 55, and is provided with a slideway formed by parallel flanges 61, which project inwardly or overhang toward the center of the wheel. A crank arm

62 is slidably mounted in the slideway, and is provided on its inner surface with a plurality of indentations 63, which are adapted to be engaged by a ball 64 carried by the wheel, and forced outwardly by the spring 65. A handle 66 is mounted on one end of the crank arm 62.

The operation of the machine above described will now be briefly set forth. The castings to be tapped or drilled, as the case may be, are placed on the work table 16, which is rotatably adjusted as desired, and the operator then presses downwardly on the foot treadle and brings the work clamping member 24 into contact with the work, this member being held in clamping contact by means of the treadle locking member 43. The hand screws 49 and 59 are then loosened, if they are not already loose, and the operator grasps the handwheel 60 and guides the tap or other tool 54 into the desired position of adjustment. During this guiding of the tool the frame 48 is freely movable vertically on the standards 47, and the saddle or frame 56 is freely movable in the guideways 57 carried by the standard 48, the counterweights 52 assisting the operator by taking up the weight of the tool, spindle, saddle, and supporting frame. When the tool has been adjusted to the desired position, the hand screws 49 and 59 are tightened, and the top or other tool is forced into the aperture and the spindle 55, which is rotated by means of the crank arm 62, the amount of leverage being determined by the position of adjustment of the crank arm 62 on the handwheel 60.

From the above description it will be seen that the adjustment of the tool may be made very quickly and accurately by the use of my improved mounting, and that the whole operation is exceedingly simple. By means of the quick and accurate adjustment, the liability to breakage of the tool is greatly decreased and the accuracy of the operation is insured.

While I have, in the above specification, described one embodiment which my invention may assume, it should be understood that the invention is capable of modification, and that modifications may be made without departing from the spirit and scope of the invention as expressed by the following claims:

1. In combination, a machine frame, supporting standards carried thereby, a supporting frame vertically adjustable on said standards, counterbalancing means for said supporting frame, a saddle adjustably mounted on said supporting frame, and a spindle mounted in said saddle for rotary and endwise movement.

2. In combination, a machine frame, supporting standards carried thereby, a supporting frame vertically adjustable on said

standards, clamping means for securing said supporting frame in the desired position of adjustment, a saddle horizontally adjustable on said supporting frame, clamping means for securing said saddle in the desired position of adjustment, and a spindle mounted in said saddle for rotary and endwise movement.

3. In a tapping machine, the combination of a main frame, a work table adjustably supported thereon, quick operating clamping means for clamping the work to the table, and adjustable tool-supporting means comprising a base adjustably mounted on the main frame and having vertical standards, a supporting frame adjustably mounted on the standards, a saddle adjustably carried by the supporting frame, a tool-carrying means mounted in said saddle for rotary and endwise movement and means for operating the tool carrying means.

4. In a tapping machine, the combination of a main frame, a work table supported thereon, quick operating yieldable clamping means for securing the work to the table, a tool spindle adjustable both vertically and horizontally on the frame and adapted for rotary and endwise movement, and means for operating the spindle.

5. In a machine of the class described, the combination of a main frame, a work table supported thereon, a clamping arm pivoted to the work table, a pedal pivoted to the frame, yieldable connections between the arm and pedal, means for holding the pedal in work clamping position, an adjustable and rotatable tool spindle mounted on the frame in operative relation to the work table, and means for operating the spindle.

In testimony whereof I affix my signature. 40

WILLIAM C. OSTERHOLM.
